UNITED STATES PATENT OFFICE.

CHARLES C. WHITTAKER, OF PITTSBURGH, PENNSYLVANIA.

HEATING SYSTEM.

1,366,988.

Specification of Letters Patent.

Patented Feb. 1, 1921.

Application filed May 22, 1919. Serial No. 298,859.

To all whom it may concern:

Be it known that I, CHARLES C. WHITTAKER, a citizen of the United States, and a resident of Pittsburgh, in the county of Allegheny and State of Pennsylvania, have invented a new and useful Improvement in Heating Systems, of which the following is a specification.

My invention relates to fluid-heating systems and it has special relation to water-heating systems for domestic purposes, such as providing hot water for actual use or for heating rooms.

One object of my present invention is to provide a system of the above-indicated character in which the amount of fuel consumed is regulated in accordance with thermostatic principles rather than being dependent upon pressure or volume considerations, as has been the case in the prior art.

More specifically stated, it is an object of my invention to provide a fluid-heating system in which a movable element, forming a portion of the gas or other fuel valve, is rendered responsive to variations in the temperature of the fluid to vary the amount of fuel supplied.

From another aspect, it is an object of my invention to provide, in a fluid-heating system, a plurality of isolated or non-communicating members respectively corresponding to the fluid supply and to the heat supply, together with an element having a materially different coefficient of cubical expansion from such members for regulating the supply of heat in accordance with the temperature of the fluid.

Another object of my invention is to provide a regulating apparatus of the above-indicated automatic character, together with means for manually adjusting the valve element to predetermine the average temperature of the fluid.

A further object of my invention is to provide a system of the class under consideration whereby the temperature of the water in the tank or reservoir may be held substantially constant when the heated water is drawn off or when the gas pressure varies, or whenever the temperature of the water changes for any other reason.

Other objects of my invention will become evident from the following detailed description taken in conjunction with the accompanying drawing, wherein Figure 1 is a view, in elevation, of a substantially com-

plete water-heating system constructed and arranged in accordance with my present invention, and Fig. 2 is an enlarged view, in longitudinal section, of the regulating apparatus that is preferably employed in carrying out my invention.

Referring to Fig. 1, the fluid-heating system here shown comprises a water tank or reservoir 1, a heater 2, a manually-operated valve 3 for conveying gas or other suitable fluid fuel to the heating system, an air-mixer 4 for providing the proper amount of air to insure complete combustion of the fuel, and my automatic regulating device 5.

The tank or reservoir 1 may be of the familiar type comprising preferably a copper incasing member 10 with which communicates a cold-water intake pipe 11, that extends downwardly to a point near the bottom of the tank, and a hot-water outlet pipe 12 for distributing the heated water for the several domestic purposes required. A pipe or tube 13 is fitted to the bottom of the tank 10 and communicates with the regulating apparatus 5, as hereinafter more fully set forth.

The water-heater 2 may also be of any well-known type and is shown as comprising essentially a coil 14 of copper pipe or the like underneath which a suitable gas or other fuel burner 15 is located, the entire apparatus being inclosed within a suitable casing 16 for the purpose of confining the heat from the burner to the fluid-carrying coil 14.

A pipe or tube 17 serves to join the burner 15 with the air-mixer 4, while other pipes 18 and 19 respectively lead out of, and into the top and the bottom of the water heater and communicate with the tank 10 and the regulating apparatus 5, respectively.

The fuel valve or cock 3 may be of any suitable type and is adapted, when closed, to prevent the access of fuel from a supply pipe 20, which is suitably connected with the source of fuel supply (not shown), to a pipe 21 that leads directly into the automatic regulating device 5.

The regulating apparatus 5, shown in section in Fig. 2, comprises a fuel-passing or conveying member 22 having a plurality of arms 23 forming a frame that is detachably secured, as by a thread, to a heatable fluid-passing or conveying member 24, the two members being isolated or non-communicating.

A pipe or passage 25 serves to connect the fuel-conveying member 22 to the air-mixer 4, while a pipe 26, preferably disposed in a horizontal position, is employed to join the fluid-conveying member 26 with a T-joint 27, within one outlet of which the pipe 13 is secured to complete the connection of the regulating apparatus 5 to the tank 10.

A valve element or movable rod 28 extends 10 between and into the two passed members 22 and 24 that respectively correspond to the supply of heat and the supply of fluid, and is governed in accordance with thermostatic principles, as more fully set forth later.

15 Referring particularly to Fig. 2, the fuel-conveying member 22 is provided with a suitable passage or opening 29 with which the pipe 21 communicates and extending in a general horizontal direction, and is also 20 provided with a vertically-located passage 30 into which the pipe 25 is fitted.

The left-hand or movable end 31 of the valve rod 28 is pointed or conical in shape 25 for coöperating with a correspondingly formed valve seat 32 through which a small aperture 33 is pierced to effect communication between the passages 29 and 30 under the illustrated conditions. However, in case the valve rod 28, while performing its regulating function, completely fills the conical recess of the valve seat, gas can still flow 30 from the inlet passage 29 through a "minimum-limit" passage 34, of relatively small diameter, to the outlet passage 30, whereby 35 the burner 15 of the heater 2 may always be maintained lighted. In this way, the desired temperature may be maintained in the tank 1 while no water is being drawn off.

For the purpose of preventing the leakage 40 of gas, or whatever fuel is employed, from the supply passage 29 to the atmosphere, the movable valve rod 28 passes through a packing gland 35, or the equivalent, and also through a similar packing gland 36 to prevent leakage of water or other fluid from the fluid-conveying member 24 to the atmosphere.

The movable valve rod 28 extends through 50 the horizontal pipe 26 and the T-joint 27 and has a threaded end 37 that is inserted in a plug 38 which, in turn, is screwed into one arm of the T-joint 27 to produce a fluid-tight connection therewith.

A lever or pin 39 is secured to the movable 55 valve rod 28, intermediate the packing glands 35 and 36, for the purpose of affording manual adjustment of the position of the rod 28 or, in other words, for helically moving said rod to vary its effective operating length. By screwing the rod 28 farther 60 into the plug 38, the balancing temperature of the system, that is, the average temperature of the heated fluid, will be increased, since a greater average volume of gas will 65 thus be allowed to flow past the cone-point

31 of the valve rod. Conversely, by manipulating the pin or lever 39 to cause the valve rod to approach the valve seat 32, such balancing temperature will be correspondingly reduced.

The movable valve rod 28 is preferably formed of brass, while the other inclosing metallic members, particularly the pipe 26, are formed of cast or wrought iron and thus have similar thermostatic characteristics. The purpose of this difference in materials is to provide a positive and material difference in the thermostatic characteristics and operation of the rod 28 and the inclosing members, whereby the materially 70 different coefficients of cubical expansion thereof serve to render the expansion or contraction of the rod 28, whereby the gas supply is diminished or increased, relatively rapid and sensitive in action.

85 For a given length of brass rod and iron pipe, the difference in expansion, per degree difference in temperature of the fluid, is fixed, and this amount will determine the degree of sharpness of the cone-point 31,— 90 the longer the rod, the sharper the point required, and the shorter the rod, the blunter should be the point.

The member 24, as previously stated, may screw-threadedly engage the arms 23 and is 95 provided with a vertical internal passage 40, within which the pipe 19 is fitted, and a horizontal passage 41 which communicates with the horizontal pipe 26.

100 As previously stated, the regulating apparatus 5 is positioned to provide a substantially horizontal location of the movable valve rod 28, whereby the most simple piping layout is provided.

The operation of the illustrated apparatus may be set forth as follows:

Assuming that the burner 15 has just been lighted and that the water in the tank 10 is, therefore, cold, since the temperature coefficient of expansion of brass is materially 110 greater than that of iron, the brass valve rod 28, the greater portion of which is surrounded by cold water, will be relatively contracted in length and, therefore, the cone-point 31 will be drawn away from the valve 115 seat 32. In this way, the size of the opening for admitting gas to the burner 15 is relatively large and a high degree of heat is thus furnished by the burner. By reason of such increased initial flow of fuel, the water in the heating coil 14 will be rapidly raised to the desired temperature.

120 As the water in the tank 10 becomes heated, the water circulating through the pipe 26 and surrounding the brass rod 28 becomes 125 increasingly warmer, to cause the rod to expand and gradually restrict the size of the opening between the cone-point 31 and the valve seat 32. Consequently, the supply of gas is limited to that which is required to 130

maintain the water in the system at the predetermined temperature.

Whenever the temperature of the water falls for any reason, such as the withdrawal of hot water through the outlet pipe 12, the correspondingly reduced temperature of the circulating water in the pipe 26, surrounding the brass rod 28, will cause the rod to contract to a greater degree than the surrounding iron members and thus automatically provide an increased supply of fuel in accordance with the degree of variation of the fluid temperature.

In this way, the movable valve rod 28 approaches or recedes from the valve seat 32 to automatically provide just the proper amount of fuel to effect a new balance between the heat supplied to the water and lost by radiation to the heat emitted by the burner 15.

The present regulating apparatus is also applicable to gas-fired hot-water furnaces for heating houses. In this case, whenever the temperature of the outer atmosphere decreases, a corresponding reduction in the house temperature occurs. Such reduction in turn will effect an increase in the amount of heat emitted by the radiators in a given time, and the effect of the corresponding decrease in the temperature of the circulating water will be communicated to the regulating apparatus 5 to increase the supply and consumption of gas, thereby maintaining the house temperature at the desired figure.

I do not wish to be restricted to the specific structural details or arrangement of parts herein set forth, as various modifications thereof may be effected without de-

parting from the spirit and scope of my invention. I desire, therefore, that only such limitations shall be imposed as are indicated in the appended claims.

I claim as my invention:

1. In a fluid-heating system, the combination with a passaged member for fluid to be heated and an isolated passaged member for fluid fuel, said members having similar co-efficients of cubical expansion, of a valve seat in the last-named passage, a single element having a materially different co-efficient of cubical expansion extending from one passage to the other for approaching or receding from said valve seat responsively to the temperature of said fluid, means for screw-threadedly engaging one end of said element in the first-named passage, and means for helically moving said element to vary the effective operating length thereof.

2. In a fluid-heating system, the combination with an apertured member for fluid to be heated and an apertured member for fluid fuel, one of said members having arms screw-threadedly secured to the other, of a valve seat within the last-named member, a regulating rod movably supported by said members and having a pointed end alined with said valve seat, and a pin extending transversely through said rod between said arms, whereby said rod may be manually caused to approach or recede from said valve seat.

In testimony whereof I have hereunto subscribed my name this 19th day of May, 1919.

CHARLES C. WHITTAKER.
